US00D693828S

(12) **United States Design Patent**
Akana et al.

(10) **Patent No.:** **US D693,828 S**
(45) **Date of Patent:** **** Nov. 19, 2013**

(54) **USB DEVICE**

(71) Applicant: **Apple Inc.**, Cupertino, CA (US)

(72) Inventors: **Jody Akana**, San Francisco, CA (US); **Bartley K. Andre**, Menlo Park, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Richard P. Howarth**, San Francisco, CA (US); **Jonathan P. Ive**, San Francisco, CA (US); **Duncan Robert Kerr**, San Francisco, CA (US); **Shin Nishibori**, Kailua, HI (US); **Matthew Dean Rohrbach**, San Francisco, CA (US); **Peter Russell-Clarke**, San Francisco, CA (US); **Christopher J. Stringer**, Woodside, CA (US); **Eugene Antony Whang**, San Francisco, CA (US); **Rico Zorkendorfer**, San Francisco, CA (US)

(73) Assignee: **Apple Inc.**, Cupertino, CA (US)

(**) Term: **14 Years**

(21) Appl. No.: **29/441,757**

(22) Filed: **Jan. 9, 2013**

Related U.S. Application Data

(63) Continuation of application No. 29/416,442, filed on Mar. 22, 2012, now Pat. No. Des. 675,215, which is a continuation of application No. 29/377,060, filed on Oct. 15, 2010, now Pat. No. Des. 658,665.

(57) **CLAIM**

The ornamental design for a USB device, as shown and described.

DESCRIPTION

FIG. 1 is a front perspective view of a USB device showing our new design;

FIG. 2 is a rear perspective view thereof;

FIG. 3 is another front perspective view thereof;

FIG. 4 is another rear perspective view thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines in the Figures show portions of a USB device which form no part of the claimed design.

1 Claim, 8 Drawing Sheets
